UNITED STATES PATENT OFFICE.

ERLE K. BAKER, OF CHICAGO, ILLINOIS, ASSIGNOR TO UNIVERSAL RIM COMPANY, OF CHICAGO, ILLINOIS, A CORPORATION OF ILLINOIS.

DEMOUNTABLE-RIM WHEEL.

1,227,990.

Specification of Letters Patent. Patented May 29, 1917.

Application filed December 31, 1912. Serial No. 739,459.

To all whom it may concern:

Be it known that I, ERLE K. BAKER, a citizen of the United States, and a resident of Chicago, Cook county, Illinois, have invented certain new and useful Improvements in Demountable-Rim Wheels, of which the following is a specification.

My invention relates to improvements in vehicle wheels and has particular reference to improvements in wheels of the demountable rim type.

The object of my invention is to simplify the construction, and reduce the cost of demountable rim wheels; to provide a wheel of the above mentioned type wherein the rim shall be retained in true load carrying concentric condition though held by a minimum number of rim clamps.

A further object of my invention is to provide a tire rim and a complementary wheel, devices carried by the wheel for quickly and easily fastening the rim in place thereon, and the rim and wheel being constructed to provide rim supports between said devices, the complete structure being built up of a minimum number of substantial parts.

A further object of my invention is to provide a wheel structure of the kind specified in which the rim has a substantially continuous circumferential bearing and the wheel is provided with a plurality of rim wedging devices spaced around the felly thereof.

My invention consists in a wheel and a complementary demountable rim, opposed wedging clamps spaced around the periphery of the wheel and adapted to be operated to wedgingly retain the rim upon the wheel, and rim supports between the rim and said periphery and between the several clamps and co-operating therewith to retain the rim in substantially true concentric condition upon the wheel, and prevent excessive distortion of the rim by the clamps.

My invention also consists in a wire or metallic wheel having a metallic fixed rim of unique construction and a complementary demountable tire rim carried on the fixed rim and held thereon by a minimum number of opposed wedging clamps spaced around the fixed rim of the wheel, and tire rim supports between the tire rim and wheel which

serve to support the tire rim at points circumferentially intermediate of the tire rim clamps, thereby preventing abnormal distortion of the tire rim by the clamps.

My invention also consists in a metallic wheel having a fixed rim provided with a centrally disposed circumferential rib or ridge of slightly smaller diameter than the internal diameter of the complementary tire rim, opposed tire rim wedging clamps spaced around the fixed rim of the wheel, said rib or ridge serving to support the tire rim at points circumferentially spaced between the clamps and thereby prevent the abnormal distortion thereof.

My invention also consists in a transversely split tire rim having means for fastening its ends together, in combination with a wheel of the foregoing description and formed to accommodate said rim end fastening means.

My invention also consists in the several arrangements and combinations of parts and in the features of construction by which the above and other objects are attained, and all as hereinafter described and particularly pointed out in the appended claims.

My invention will be more readily understood by reference to the accompanying drawings, forming part of this specification, and in which:

Fig. 1 is a side elevation of a pneumatic tired wheel illustrating one embodiment of my invention.

Fig. 2 is an enlarged detailed section of the wheel on the line 2-2 of Fig. 1.

Fig. 3 is a similar section on the line 3-3 of Fig. 1.

Fig. 4 is a plan view of the inner surface of the metal band which forms the felly of the wheel showing one of the rim clamping devices.

Fig. 5 is an enlarged view illustrating, in an exaggerated form, the rim distorting action of the rim clamps.

Fig. 6 is an enlarged detailed section through one of the rim clamping devices on the line 6-6 of Fig. 5.

Fig. 7 is a side elevation of an automobile wheel illustrating a modification of my invention, in which spaced studs take the place of the circumferential rim shown in the other views.

Fig. 8 is an enlarged detailed section on the line 8—8 of Fig. 7.

Fig. 9 is a similar view on the line 9—9 of Fig. 7.

Fig. 10 is a side elevation of an automobile wheel similar to that shown in Fig. 1 except that it is mostly of wood.

Fig. 11 is an enlarged section taken on the line 11—11 of Fig. 10.

Fig. 12 is a circumferential section on the line 12—12 of Fig. 10 showing the slot formed in the felly band.

Fig. 13 is an enlarged transverse section on the line 13—13 of Fig. 10.

Fig. 14 is a fragmentary side elevation of a wood wheel showing a construction similar to that illustrated in Fig. 7.

Fig. 15 is an enlarged transverse section on the line 15—15 of Fig. 14.

Fig. 16 is a side elevation of a metallic wheel showing another modification of my invention.

Fig. 17 is an enlarged section taken on the line 17—17 of Fig. 16.

Fig. 18 is a section taken in the plane of the wheel on the line 18—18 of Fig. 17.

Fig. 19 is an enlarged transverse section of the wheel taken on the line 19—19 of Fig. 16.

Fig. 20 is a similar section taken on the line 20—20 of Fig. 16.

Fig. 21 is a transverse section through one of the doweling pins on the line 21—21 of Fig. 16.

Fig. 22 is a fragmentary side elevation, partly in section, of a wheel showing a modified construction.

Fig. 23 is a plan view of the tire rim illustrated in Fig. 22 showing the connecting plate.

Fig. 24 is a transverse section on the line 24—24 of Fig. 22.

Fig. 25 is a view similar to Fig. 22 showing another modification of my invention.

Fig. 26 is a plan view of the tire rim shown in Fig. 25 illustrating the manner of doweling the ends of the rim together.

Fig. 27 is an enlarged transverse section of the rim and felly on the line 27—27 of Fig. 26.

My invention provides a wheel which satisfies the requirements not only from a manufacturing standpoint, but that from the user as well, for the reason that the wheel is not only capable of being manufactured at a low cost, but is so strong, rigid and light that it is capable of remaining in substantially true condition for a great length of time even though subjected to severe strains produced by fast driving over rough country roads.

Furthermore, my wheel as a whole consists of but very few parts, either to be manufactured or to be manipulated in use, and, even though the rim is wedgingly sup-

ported at widely separated points, it is not thereby distorted out of its substantially true circular condition, for I support the rim at points substantially midway between the widely separated wedging devices and the rim is thereby held both against distortion by the wedging devices and against abnormal flexure from extreme road shocks.

I have, in the drawings, illustrated my invention as applied to the development of wheels known as metallic wheels and to those known as wood wheels, and it will be understood that some of the features of my invention are equally applicable to both.

In my improved wheel I provide a wheel the periphery of which is but slightly less than the normal internal circumference of the demountable rim to be used therewith. The wheel therefore centers the rim when the rim is placed thereon, and the rim can then be easily secured in true concentric condition upon the wheel. I also provide a relatively small number of wedging devices each of which comprises a pair of oppositely disposed wedges adapted to engage opposite edges of the rim. The opposed wedges are in each case connected by a clamping bolt which, when it is rotated in one direction, serves to force the wedges toward each other and thus wedgingly clamp the rim upon the wheel. It will be understood at once that the rim being a metallic ring is capable of being forced or flexed outwardly by the wedges and, as these wedges are widely separated on the felly of the wheel, the rim would naturally be distorted by the wedges, the portions of rim between the wedges being distorted inwardly when the wedges are tightened. But as the wheel is only slightly smaller than the rim, the latter is held against the described distortion.

For this purpose I preferably provide the wheel periphery with a centrally disposed circumferential rib or ridge. This centrally disposed rib provides annular slots or openings, both at the front and the rear of the wheel for the reception of the wedge clamps, and when the wedges are forced toward each other to secure the rim upon the wheel the rim is thereby deflected inwardly at points between the wedges and caused to find bearings upon the rib and be thereby braced and supported in position. Under some conditions I replace the centrally disposed rib by projections disposed upon the wheel and arranged intermediate of the wedging clamps and of such a radial depth that, taken together, they provide a fixed rim which is but slightly less in effective diameter than the inner diameter of the rim.

As rims which are split or cut apart at one point in their circumference are particularly adapted for use in my invention, I have shown several methods of connecting

the ends of the rims together and the necessary modifications of the wheel periphery for use therewith. Thus, to provide room for the plate rim and connecting means, whether long or short, I remove or displace a portion of the central rib or ridge on the wheel periphery. Furthermore, I sometimes make use of the connecting means as a driver to prevent the circumferential displacement of the rim upon the wheel, and in such cases provide co-acting shoulders on the rib. I preferably make the fixed felly out of cold rolled sheet metal stock, forming the same into a ring and welding the ends together, and then forming the ring in suitable rolls to produce the cross section desired. This method of manufacturing is relatively cheap. The parts can be produced rapidly, and accurately to size, and in the form of felly ring which I have illustrated the necessary holes or openings can be quickly produced by means of the ordinary punching machines. I am enabled, therefore, to produce wheels embodying my invention at a minimum manufacturing cost.

In Figs. 1 to 9 inclusive, I have shown the application of my invention to the production of metallic or wire wheels;

In Figs. 10 to 15, inclusive, I have shown the invention as embodied in wood wheels;

Figs. 16 to 21, inclusive, illustrate a modified form of wheel rim for wire or metallic wheels; and

Figs. 22 to 27, inclusive, illustrate some of the detail constructions particularly useful in connection with wood wheels.

The wheel illustrated in Figs. 1 to 5, inclusive, comprises a hub A, a metallic fixed rim B and suitable wire spokes C, connecting the hub and fixed rim. These parts comprise the wheel proper, and it is intended to carry a tire rim D. In the form illustrated in the drawings this rim D is adapted to carry a pneumatic tire E. The wheel proper carries a number of rim clamping devices F spaced around the periphery thereof. In the wheel illustrated, I have shown it as being supplied with five of these clamping devices substantially equally and widely spaced around the wheel. Each of these rim clamping devices comprises an abutment block f¹ mounted upon the rear edge b¹ of the fixed rim and provided with an outer wedging surface f² adapted to provide a wedging seat for the tire rim D. This abutment block is provided with a threaded opening f³ arranged transversely of the fixed rim and adapted to receive the threaded end of the clamping bolt f⁴. This bolt carries at its opposite end a wedging clamp f⁵ rotatably mounted thereon between the head f⁶ thereof and a circumferential shoulder f⁷. The outer surface f⁸ of this clamp is formed similarly to the

wedging surface f² of the abutment block, and the bolt when screwed into the threaded opening f³ serves to clamp the rim D between the two opposite wedging surfaces of the abutment block f¹ and the wedge clamp f⁵. As the rim clamping devices are widely separated, and as the tire rim is not an absolutely rigid ring, but, on the other hand, is somewhat flexible, these wedging devices tend to force the rim radially outward when the bolts are operated to clamp the rim. This serves to distort the rim to a certain extent, that is, the wedges tend to force the rim outwardly at circumferentially separated points and the portion of the rim between the wedges conversely tends to move inwardly and the rim is thus distorted out of its true circumferential condition. I have exaggerated the distortion in Fig. 5. I prevent the wedges from causing any very great distortion of the rim by providing rim supports between the two rims and between the rim clamping devices. These rim supports preferably comprise a central circumferential rib or ridge b². This rib b² I make slightly less in external diameter than the normal internal diameter of the tire rim D, and consequently this rib or ridge does not hinder the easy mounting of the rim upon the wheel proper. This rib being slightly less in diameter or circumference than the inner diameter of the tire rim serves to provide seats for the rim at points intermediate of the several rim clamping devices, and consequently the rim is supported not only upon the tapered rim seats formed by the opposed clamping devices, but also at points substantially midway between these devices; that is, upon the outer surface b³ of the central rib b². It is to be noted that when the clamping bolts f⁴ are backed out, the rim clamps f⁵ can be rotated to positions where they will not interfere with the free removal of the tire rim D. The rib b² is considerably narrower than the outer face of the fixed rim and consequently there are circumferential spaces b⁴ and b⁵ between the rim and the wheel adapted to receive the inner ends of the opposed rim clamps. Fig. 2 shows the space between the inner surface of the tire rim and the outer surface of the rib b², and Fig. 3, which is a section taken substantially midway between adjacent clamping devices, shows these two parts in contact with each other. The rear rim clamp f⁵ is shown in Fig. 2 as overlapping upon the rear edge of the fixed rim and I further secure and hold this block in position by means of rivets f⁹ which pass through suitable ears f¹⁰ provided upon the forward end of this block.

Fig. 6 illustrates a slightly modified form of fixed rim B¹. Instead of the main part thereof being substantially parallel or cylind-

drical, as illustrated in Figs. 1 to 3, it is beveled from its forward and rear edges inwardly toward the centrally disposed rib or ridge b^2 , and, although thus somewhat 5 heavier, serves substantially the same functions and purposes, that is, to provide a centrally disposed surface slightly less in diameter than the inner diameter of the tire rim and capable of supporting the rim circum- 10 ferentially between the clamping devices.

In Figs. 7 to 9 inclusive I have shown a slightly modified form of rim support. In this instance the fixed rim B^2 is straight or cylindrical in form and sufficiently less in 15 external diameter than the internal diameter of the tire rim to provide a circumferential space b^6 for the reception of the inner ends of the opposed rim clamps f^{11} and f^{12} . As shown in Fig. 9, the rim support comprises 20 a plurality of projections b^7 secured to and projecting radially from the fixed rim B^2 adjacent to the rear edge thereof, and similar projections b^8 secured to and projecting from the tire rim transversely in line with 25 the projections b^7 and spaced therefrom sufficiently so that when the tire rim is in position upon the fixed rim the inner ends of these projections b^8 will contact with the outer surface of the fixed rim. These projections b^7 and b^8 are arranged in pairs 30 around the periphery of the fixed rim and tire rim and spaced substantially midway between the clamping devices, as illustrated in Fig. 7, and they serve to support the rim 35 in opposition to the distorting tendency of the clamps at points substantially midway between adjacent clamps. These projections thus provide a rim seat of slightly less diameter than the inner diameter of the rim 40 and adapted to coöperate with the rim clamping devices to hold or maintain the tire rim in substantially its true circular condition, both as regards the strains incident to the clamping of the rim upon the 45 wheel and those incident to actual use under load. The fixed rims B , B^1 and B^2 are all relatively heavy in cross section and are each of a form adapted to be made by what is known as the "hot process" as distinguished 50 from a process of making fixed rims out of sheet metal, for the sections of said rims are such as cannot readily be formed by what is known as the "cold rolled method." It is to be understood that the fixed rims of 55 the sections illustrated can as readily be applied to the production of wood wheels, and in Figs. 14 and 15 I have illustrated a wood wheel having projections b^7 and b^8 similar to those shown in Figs. 7 and 9.

60 In wood wheels it is possible to make the felly bands of considerably thinner material and form them up by the "cold rolling process," and in Figs. 10 to 13 inclusive, I have illustrated such a felly band. In this instance the felly band B^8 is formed with a

central raised rib or ridge b^9 similar to the central rib b^2 illustrated in Figs. 1 to 3. This circumferential rib b^9 provides the circumferential spaces b^4 and b^5 for the reception of the wedging rim clamps and also 70 provides the rim supports circumferentially spaced between the rim wedging devices.

It should be understood that the rim D may be either a split rim or a non-split rim, depending on which form it is desired to 75 use. In the drawings, I have shown this rim as being split or cut apart at one point d^1 in its circumference and, as shown in Fig. 1, I connect the two rim ends d^2 and d^3 together by means of a plate d^4 which 80 conforms to and with the inner periphery of the rim. The rim is provided with two inwardly projecting dowel pins d^5 upon each of its ends, and the plate is provided with suitable dowel openings d^6 to receive these 85 dowel pins. These dowel pins are long enough to project into suitable openings provided in the felly band, and the rim is thereby doweled to the felly band. The felly band, the plate and the rim are provided with registering holes adapted to receive the tire valve stem e^1 . The valve stem is preferably arranged adjacent to the split 90 in the rim. In the form of wheel illustrated in Fig. 1, I provide the space for the connecting plate d^4 by cutting away the rib or ridge b^2 . In the form of fixed rim shown 95 in Figs. 10 to 13 inclusive, I provide the space for the connecting plate d^4 by cutting off or cutting away the formed-up circumferential rib b^9 and in doing so I provide an 100 elongated slot b^{10} in the felly band. This slot serves to receive the dowel pins d^5 . The outer dowel pins b^5 contact with the ends 105 b^{11} of the slot and thereby dowel the rim upon the wheel. As there are many advantages in the "cold rolled" fixed rim I have 110 devised and illustrated a form of fixed rim B^4 suitable for wire or metallic wheels and made of sheet metal. I have illustrated this 115 form of fixed rim in Figs. 16 to 21, inclusive. The difficulty with fixed rims made up of sheet metal which can be cold rolled is that the fixed rim itself lacks rigidity. The 120 fixed rim B^4 however is very rigid as I have strengthened it by providing it with an inwardly projecting flange b^{12} at one side and in position to serve as an abutment for the rim clamps. This makes a fixed rim which is adapted to withstand the strains to which 125 it is subjected in use. In this form the rear rim clamps f^{14} do not extend to the forward edge of the fixed rim, as illustrated in Figs. 2 and 3, but are secured to the rear portion thereof, the clamping bolts f^4 finding bearings at their forward ends in the flange b^{12} which is provided with suitable openings b^{13} to receive the clamping bolts. In this form of my invention, instead of cutting away 130 the circumferential rib b^{14} , to provide space

for the rim connecting plate d^4 similar to the construction illustrated in Figs. 10 to 13, I deform the rib, forcing it back radially into coincidence with the body of the felly, as clearly shown in Fig. 17, and I thereafter provide it with holes b^{15} to receive the dowel pins d^5 , as clearly shown in Fig. 18. This construction provides a fixed rim which is as strong at that portion where it receives the connecting plate as at other parts of its circumference.

In Figs. 22 to 24 I have shown a method of providing space in a wood wheel for the rim end connecting plate d^4 . Instead of cutting the central circumferential rib b^{14} entirely away, as shown in Figs. 11 to 13, I make the plate d^4 considerably thinner and reduce or cut away the rib to receive this thin plate. In Figs. 25 to 27 I have illustrated a modified form of connecting and doweling plate. In this form the connecting plate d^{12} is very much smaller and I dowel the ends of the rim together by means of a small dowel d^{13} which is received between the two ends of the rim, each end being provided with a small half-round opening d^{14} which together form an opening adapted to receive the dowel pin d^{13} . At times when the rim is not in position on the wheel I retain this small plate d^{12} in its position by means of a nut e^2 against the inner face of the rim, the plate being provided with the opening d^{14} through which the valve stem e^1 passes. The valve stem thus serves to secure the plate d^{12} to one end of the rim, and to prevent the separation of the two ends of the rim I provide a second dowel pin d^{17} on the opposite end of the plate d^{12} , which is received within a suitable opening d^{18} provided in the end d^{11} of the rim. The plate d^{12} thus serves not only to carry the dowel pin d^{13} which prevents the relative transverse movement of the two ends of the rim but also serves to hold the two ends of the rim against circumferential separation.

In mounting the tire rim upon the wheel proper, the portion of the rim carrying the valve stem is first placed in position, the valve stem being passed radially through the opening in the fixed rim. The rim end connecting plate is seated upon or against the fixed rim and then the balance of the rim is swung into place, being centered by the circumferential rib or the spacers. The rim is then secured on the wheel by manipulating the relatively few wedging devices. It will now be clear that the rim can be quickly and easily removed from the wheel by loosening the clamps and reversing the operation.

It will now be understood that by my invention I am enabled to provide a strong wheel, of the demountable rim type, of light weight, and at low cost, and one in

which the rim can be mounted and dismounted in a minimum time and with little effort, and one which, although provided with but few rim fasteners, is capable of retaining the rim in substantially true circumferential condition at all times.

As many modifications of my invention will readily suggest themselves to one skilled in the art, I do not limit or confine my invention to the specific structure herein shown and described.

I claim:

1. A vehicle wheel comprising a wheel in combination with a plurality of pairs of opposed rim wedging clamps spaced around the wheel periphery and adapted to force the rim outwardly at a plurality of points, and a rim support carried by the wheel and extending circumferentially, intermediate of said pairs of clamps, to prevent excessive distortion of a rim upon the wheel.

2. A vehicle wheel comprising a wheel in combination with a plurality of rim retaining devices carried by and spaced around the wheel, each thereof comprising two complementary opposed wedging clamps and a co-operating bolt, rim supporting means arranged between the rim and the wheel and intermediate of said clamps and adapted to prevent excessive distortion of a rim by the clamps.

3. A vehicle wheel comprising a wheel in combination with a plurality of opposed wedging rim clamps carried by and spaced around the wheel, a centrally disposed circumferential rib or ridge on the wheel of slightly less circumference than the inner circumference of the rim, and adapted to support a rim intermediate of the clamps.

4. A vehicle wheel comprising a wheel proper having a fixed rim and a complementary demountable rim, said fixed rim being provided with a centrally disposed circumferential rib or ridge slightly smaller in diameter than the internal diameter of the rim, a plurality of wedging rim engaging devices spaced around the fixed rim and adapted to secure the demountable rim thereon, said rib serving to prevent the collapse of the demountable rim at points circumferentially between said wedging devices.

5. In a metallic vehicle wheel a sheet metal fixed rim substantially L-shaped in cross-section and provided on its outer periphery with a centrally disposed circumferential rib forming a rim seat.

6. In a vehicle wheel a sheet metal fixed rim having a centrally disposed circumferentially formed up rib providing a rim seat in combination with a tire rim having a cylindrical inner periphery whereby circumferential spaces are provided to receive rim clamps.

7. In a vehicle wheel a metallic fixed rim

having a circumferential centrally raised rim seat, in combination with a tire rim thereon having an internal diameter slightly greater than the external diameter of the
5 rim seat and a plurality of wedging devices carried by the wheel for removably holding the rim in place.

In testimony whereof, I have hereunto set my hand, this 24th day of December, 1912, in the presence of two subscribing witnesses.

ERLE K. BAKER.
